(57) **CLAIM**

The ornamental design for a disinfecting unit label for a medical device, as shown and described.

DESCRIPTION

FIG. 1 is top front isometric view of a disinfecting unit label for a medical device;

FIG. 2 is a top view of the disinfecting unit label for a medical device;

FIG. 3 is bottom view of the disinfecting unit label for a medical device;

FIG. 4 is a left side view of the disinfecting unit label for a medical device;

FIG. 5 is a right side view of the disinfecting unit label for a medical device;

FIG. 6 is a front view of the disinfecting unit label for a medical device;

FIG. 7 is a rear view of the disinfecting unit label for a medical device; and,

FIG. 8 is a top front isometric view of the disinfecting unit label for a medical device of FIG. 1 attached to a syringe, said syringe shown as an environmental structure in broken lines.

Portions of the article shown in broken lines form no part of the claimed design.

The solid black shading represents color contrast.

1 Claim, 5 Drawing Sheets
